INVENTOR

BY *Victor J. Evans*

ATTORNEY.

UNITED STATES PATENT OFFICE.

JOHN M. CAVITCH, OF MUNISING, MICHIGAN.

DRYING MACHINE.

Application filed July 6, 1923. Serial No. 649,937.

To all whom it may concern:

Be it known that I, JOHN M. CAVITCH, a citizen of the United States, residing at Munising, in the county of Alger and State 5 of Michigan, have invented new and useful Improvements in Drying Machines, of which the following is a specification.

This invention relates to a drying machine, and an object of the invention is to 10 provide a machine particularly designed for drying wood, veneer and various other articles, and an object of the invention is to provide a drying machine which will utilize air passing at a relatively high rate of speed 15 through the dryer, for removing the moisture from various articles placed in the dryer.

Another object of this invention is to 20 provide a dryer structure as specified which is particularly adaptable for use in drying veneer, rolling pin blocks, short lumber, butter moulds, shells and handles, potato masher and various other articles of wooden 25 ware, utilizing air as the drying agent.

Heretofore it has been the practice to dry 30 wooden ware, veneer or wooden blocks by heated air or steam or both, and the various dryers in use utilizing this principle require considerable time to properly dry the wood and also cause checking of the ends of the wood resulting in considerable loss. Sometimes the wood is painted on the ends 35 to prevent such checking but it has been found that even this practice does not entirely eliminate the checking or cracking of the wood.

In the present centrifugal drying machine 40 which utilizes air as the drying agent all checking and warping of the wood is eliminated and it has been found that the wood may be thoroughly dried in a much shorter time than is required by dryers of the type above specified.

A further object of this invention is to 45 provide a rotary dryer which is designed to increase the velocity of the air passing therethrough, which increasing the velocity of the air is caused through the formation of novel air inlets and air guiding blades 50 or vanes within the dryer which guide the air through the dryer and tangentially from the circumference of the dryer during its rotation, resulting in effective and efficient drying of the material placed in the 55 dryer.

Other objects of the invention will appear in the following detailed description taken in connection with the accompanying drawings wherein:—

Fig. 1 is a top plan of the improved 60 dryer.

Fig. 2 is a vertical section through the dryer taken on the line 2—2 of Fig. 1.

Referring more particularly to the drawings, the improved centrifugal drying machine comprises a bed plate 1 which is anchored by suitable anchoring bolts 2 to a suitable cementitious foundation 3. The bed plate 1 is circular or ring-like in shape 65 and is provided with an annular raceway 4 in its upper face in which bearing rollers 5 are mounted. The bearing rollers 5 engage in an annular raceway 6 formed in the under surface of the rim 7 of the rotary carrier of the dryer structure. The rim 7 70 is connected to the hub 8 by suitable spokes 9 which may be bolted or otherwise suitably attached to the rim and the hub. The rim has a beveled gear 10 formed on its under surface adjacent its perimeter, which 75 beveled gear meshes with a beveled gear 11 mounted upon the driving shaft 12. The driving shaft 12 is supported by suitable 80 bearings 13 and may be driven from any suitable power source through the medium 85 of any suitable power transmitting mechanism.

The central shaft 14 of the rotary dryer extends axially through the hub 8 and through a bearing collar 15, as clearly 90 shown in Fig. 2 of the drawings and it has collars 16 and 17 attached thereto adjacent its lower and upper ends respectively. A plurality of spokes 18 are connected to the flange 19 formed on the collar 17 and these spokes 18 radiate from the axis of the shaft 14 and are connected in any suitable manner to vertical channel irons 20. The vertical channel irons 20 have their lower 95 ends angled as shown at 21 and attached to the rim 7 by cap screws 22 or in any other approved manner. A relatively heavy mesh screen 23 is attached to the channel irons 20 and forms the sides of the basket of the rotor. The channel irons are braced 100 at spaced vertical points by annular rods 24.

A pair of spokes 18, namely those indicated by 18' in the drawings, have extensions 25 formed thereon which project beyond the perimeter of the basket structure 110

of the rotor, which have air guiding plates 26 attached thereto. The air guiding plates 26 are also attached to the spokes 18 next to the spokes 18', as clearly shown in Fig. 1 of the drawings, and they curve convexly and extend tangentially from the perimeter of the rotor. The guides 26 extend the full height of the rotor and their lower ends are braced and supported by suitable bracing 10 and supporting rods 27. The guides 26 are adapted to direct air inwardly into the basket or rotor of the dryer during rotation of the latter, which air passing in its bisecting curved path relative to the perimeter of the rotor will strike the speed increasing and deflecting blades 28, and these blades will alter the path of the air and increase its velocity at its outlet from the basket, owing to the fact that the blades extend substantially straight for the major portion of their lengths and the air entering the rotor in the path directed by the guides 26 will strike against the straight portions of the blades and travel there along, during rotation of the basket, for a short distance, after which it will be directed by the relatively sharp curved portions 29 of the blades, in a sharply turned path tangentially of the circumference of the basket and project from the basket at a highly increased velocity causing substantially a vacuum pull through the basket which will draw moisture out of any wooden articles or pieces of wood or similar material in the basket. The blades 28 are braced by suitable braces 30.

The guides or wings 26 are adjustable at their free edges by means of the nuts 31 which are threaded upon the extensions 25 and brace rods 27 so as to permit adjustment 40 of the mouth or inlet formed by the guides so as to direct the proper volume of air at the required speed into and through the basket during rotation thereof. The air action above specified causes a sifonic action 45 on the pores of the wood, holding the pores opened while the centrifugal force caused by the rotation of the basket will throw the moisture to the surface of the wood. The strong suction created by the sharp curves 50 on the blades 28 will carry the moisture away from the surfaces of the wood and from the machine. In operation, the machine should be rotated until all the moisture is exhausted from the wood and when 55 this is done, and the speed of rotation of the basket reduced or stopped the pores of the wood contract causing the wood to shrink and by this means the fibers or pores of the wood are all closed up without any stress or 60 strain on any particular part of the wood, which prevents checking or warping of the wood or articles being dried.

It is to be understood that the device is particularly designed for drying green wood for if the wood has become surface dried,

the pores of the wood at the surface are closed to such an extent as to prevent the proper action of the air thereon and such surface dried wood must however, be dried by a steam process to reopen the surface pores after which it can be dried in the present centrifugal dryer.

The wooden ware or articles to be dried are placed within the basket upon the spokes 9 and rim 7 or upon any suitable platform 75 that may be placed therein. It will be apparent that any number of articles or quantity of wood may be dried and it will not be necessary to wait until a sufficient quantity has accumulated for drying to completely 80 fill the dryer structure as is necessary with the present approved type of drying kilns or steam dryers now in use. It will also be apparent that the material to be dried need not be neatly stacked within the basket but 85 may be placed therein in any desired manner.

It is, of course, to be understood that the invention may be constructed in other manners and the parts associated in different relations and, therefore, I do not desire to be limited in any manner except as set forth in the claims hereunto appended.

Having thus described my invention what I claim is:

1. A dryer comprising a foraminous article containing basket, air guide plates carried by the basket at diametrically opposed points and curving inwardly for guiding air into the basket, and means for adjustably supporting the mouthed edges of said guide plates.

2. A dryer comprising a basket having foraminous sides, means for rotating said basket about a vertical axis, means for directing air tangentially into the basket, and air guiding plates within the basket for directing the air outwardly from the basket in streams tangentially of the perimeter of the disc.

3. A dryer comprising an article containing basket, means for directing air into the basket, and air guiding blades within the basket for directing the air out of the basket in paths tangentially of the perimeter of the basket.

4. A dryer comprising an article containing basket, means for directing air into the basket, air guiding blades within the basket for directing the air out of the basket in paths tangentially of the perimeter of the basket, means for rotating said basket, said blades being shaped whereby the velocity of the outgoing air from the basket will be materially increased over the velocity of the air entering the basket.

5. A dryer comprising a foraminous article containing basket, means for rotating said basket, and air guiding plates carried by the basket at diametrically opposed

points and curving inwardly substantially tangentially of the perimeter of the basket for guiding air into the basket.

6. A dryer comprising a foraminous article containing basket, means for rotating said basket, air guiding plates carried by the basket at diametrically opposed points and curving inwardly substantially tangentially of the perimeter of the basket for guiding air into the basket, and means for adjustably supporting the mouth edges of said air guiding plates.

7. A dryer comprising a foraminous article containing basket, means for rotating said basket, air guiding plates carried by the basket at diametrically opposed points and curving inwardly substantially tangentially of the perimeter of the basket for guiding air into the basket, and air guiding blades within the basket and shaped to receive the air guided into the basket by said blades and

direct it out of the basket in sharp curved paths for increasing the velocity of the outgoing air over the velocity of the incoming air.

8. A dryer comprising a foraminous article containing basket, means for rotating said basket, air guiding plates carried by the basket at diametrically opposed points and curving inwardly substantially tangentially of the perimeter of the basket for guiding air into the basket, air guiding blades within the basket and shaped to receive the air guided into the basket by said blades and direct it out of the basket in sharp curved paths for increasing the velocity of the outgoing air over the velocity of the incoming air, and means for adjustably supporting the mouth edges of said air guiding plates.

In testimony whereof I affix my signature.

JOHN M. CAVITCH.
